UNITED STATES PATENT OFFICE.

HENRY P. WEALE AND GEORGE L. ADAIR, OF BOSTON, MASSACHUSETTS,
ASSIGNORS, BY DIRECT AND MESNE ASSIGNMENTS, TO THE WEALE-
ADAIR LUBRICATOR COMPANY, OF SAME PLACE.

SELF-LUBRICATING CAR-AXLE BOX.

SPECIFICATION forming part of Letters Patent No. 558,329, dated April 14, 1896.

Application filed August 30, 1895. Serial No. 560,972. (No model.)

To all whom it may concern:

Be it known that we, HENRY P. WEALE and GEORGE L. ADAIR, of Boston, in the county of Suffolk and State of Massachusetts, have invented certain new and useful Improvements in Self-Lubricating Car-Axle Boxes, of which the following is a specification.

This invention relates to a car-axle box which is provided with an oil-chamber below the journal of the axle and with means for continuously raising the oil into contact with the journal.

The invention has for its object, first, to provide an axle-box with improved means for excluding dust from the journal and from the oil-chamber, and, secondly, to provide an improved oil-feeding device adapted to be applied to an axle-box of ordinary construction and to be readily removed from the box.

To these ends the invention consists in the improvements which we will now proceed to describe and claim.

Of the accompanying drawings, forming a part of this specification, Figure 1 represents a longitudinal section of a car-axle box provided with our improvements. Fig. 2 represents a section on line 2 2 of Fig. 1. Fig. 3 represents a perspective view of the lubricating attachment removed from the axle-box. Figs. 4 and 5 represent perspective views showing the parts of the dust-guard.

The same letters and numerals of reference indicate the same parts in all the figures.

In the drawings, *a* represents a car-axle box, which may have the ordinary general form, it being open at its inner end for the reception of the axle *b* and having an opening *a'* at its outer end affording access to the interior of the box, said opening having the usual detachable cover *a''*.

The box is of sufficient depth to provide an oil-chamber *a³* below the journal *b'* of the axle, the opening *a'* being above said chamber and communicating therewith.

So far as the features thus far described are concerned, the box is of ordinary construction, the chamber *a³* being the space that is ordinarily filled with cotton-waste saturated with lubricating material.

In carrying out our invention we provide at

the inner end of the box two parallel walls *a⁴* *a⁵*, each having an enlarged opening *a⁶* for the reception of the axle, said walls forming a packing or dust-guard receiving chamber *a⁷*, which surrounds the axle. The proximate sides of said walls are preferably trued to form smooth flat seats *3 4* for the dust-guard plates presently described, and the openings *a⁶* are of sufficient size to permit the necessary independent movements of the axle and box.

In the chamber *a⁷* we place a dust-guard, which comprises two plates *c c'*, each having an opening *c²*, formed to closely fit the axle. The outer sides of said plates are trued to snugly fit the seats *3 4*, the plates being free to move with the axle, so that their outer sides are in sliding contact with the said seats. The plates *c c'* are held yieldingly against the seats *3 4* by means of springs *d d'*, interposed between the plates, said springs being here shown as attached by the plate *c* and bearing at their free ends against the plate *c'*.

The plate *c* is provided with a flange *c⁴*, which partially surrounds the opening *c²* in said plate and forms the margin of a pocket between the plates *c c'* for the reception of fibrous packing material *e*, which may be cotton-waste or any other suitable material.

It will be seen that the described dust-guard, comprising the plates *c c'*, springs *d d'* and flange *c⁴*, maintains a dust-tight joint around the axle and adapts itself readily to the relative movements of the axle and box.

f represents an arm or rod, which is screw-threaded at its outer end and passes through a hole formed in the outer end of the box *a* above the oil space or chamber *a³*, the said arm being secured to the box by nuts *f' f''* on said threaded portion. The arm *f* is formed to extend downwardly to the lower portion of the oil-chamber and inwardly to a point under the journal *b'*. To the inner portion of the arm *f* is connected a standard *f³*, preferably by means of a plate *f⁴*, riveted to the inner end of the arm and constituting an extension thereof, although it is obvious that the standard may be formed directly on the arm, the latter being suitably lengthened. To the standard *f³* is pivoted a lever *f⁵*, hav-

ing arms f^7 f^7 at each end, in which are bearings for the shaft of a roll f^8 . The other end of the lever f^5 has a weight f^9 , adapted to exert an upward pressure on the roll f^8 . The 5 said roll is located in the oil-chamber a^3 below the journal b' and is pressed by the weight against said journal. The roll is therefore rotated by contact with the journal, and as its lower portion is close to the bottom 10 of the oil-chamber its rotation causes a continuous supply of oil to the journal, the oil being raised by the periphery of the roll and presented to the journal, which is thus kept constantly lubricated. Loss of oil from the 15 box is prevented by the dust-guard, so that a single charge of oil will last a long time.

It will be seen that the arm f , provided, as shown, with means whereby it may be detachably secured to the outer portion of the 20 box a above the oil-chamber, and the roll f^8 , supported by said arm in the accumulation of oil in the box, constitute a lubricating attachment that can be readily applied to an ordinary axle-box and can be as readily removed for repairs, no adaptation of the box 25 being required other than the formation of the hole for the reception of the outer end of the arm f .

We claim—

30 1. A car-axle box having the parallel walls a^4 a^5 at its inner end, each having an opening for the reception of the axle, said walls being separated by a packing space or chamber;

combined with a dust-guard comprising, first, a plate c loosely seated on one side of said 35 chamber and having an orifice closely fitting the axle and a packing-retaining flange partly surrounding the axle; secondly, an independent plate c' loosely seated on the opposite side of said chamber and having an orifice 40 closely fitting the axle, and thirdly, springs interposed between the plates c and c' and pressing said plates against their seats.

2. A lubricating attachment for car-axle boxes, the same comprising the arm f provided at its outer portion with means such as a screw-thread and nuts, whereby it may be detachably secured to the outer end of an axle-box, and at its inner portion with a standard f^3 ; a lever pivoted to said standard 45 and provided at one end with roller-bearings and at the other end with a weight; and a lubricating-roll journaled in said bearings and pressed upwardly by the said weight, the arm being formed to hold the roller in position to bear yieldingly against the lower portion of the journal.

In testimony whereof we have signed our names to this specification, in the presence of two subscribing witnesses, this 5th day of 60 August, A. D. 1895.

HENRY P. WEALE.
GEORGE L. ADAIR.
